(57) **CLAIM**

The ornamental design for a liquor decanter base, as shown and described.

DESCRIPTION

FIG. 1 is a top, front perspective view of a first embodiment of a liquor decanter base, showing my new design;

FIG. 2 is a top plan view of FIG. 1;

FIG. 3 is a bottom plan view of FIG. 1;

FIG. 4 is a left-side elevational view of FIG. 1;

FIG. 5 is a right-side elevational view of FIG. 1;

FIG. 6 is a front elevational view of FIG. 1;

FIG. 7 is a rear elevational view of FIG. 1;

FIG. 8 is a top, front perspective view of a second embodiment of a liquor decanter base, showing my new design;

FIG. 9 is a top plan view of FIG. 8;

FIG. 10 is a bottom plan view of FIG. 8;

FIG. 11 is a left-side elevational view of FIG. 8;

FIG. 12 is a right-side elevational view of FIG. 8;

FIG. 13 is a front elevational view of FIG. 8; and,

FIG. 14 is a rear elevational view of FIG. 8.

The broken lines in FIGS. 1 and 8 depicting glasses and a rifle-shaped decanter depict environmental subject matter that forms no part of the claimed design. The remaining broken lines depict portions of the liquor decanter base that form no part of the claimed design. The dot-dash broken lines show a boundary of the claimed design, and form no part of the claimed design.

1 Claim, 8 Drawing Sheets
